UNITED STATES PATENT OFFICE

153,581

DESIGN FOR AN INSULATING SIDING CORNER UNIT

Robert D. Bordeaux, Chicago, Ill., assignor to
Bird & Son, Inc., East Walpole, Mass., a cor-
poration of Massachusetts

Application October 8, 1948, Serial No. 149,050

Term of patent 14 years

(Cl. D68—1)

To all whom it may concern:

Be it known that I, Robert D. Bordeaux, a citizen of the United States, residing at Chicago, in the county of Cook and State of Illinois, have invented a new, original, and ornamental Design for an Insulating Siding Corner Unit, of which the following is a specification, reference being had to the accompanying drawing, forming part thereof.

Fig. 1 is a perspective view of an insulating siding corner unit embodying my new design; and

Fig. 2 is a cross sectional view taken on line 2—2 of Fig. 1.

I claim:
The ornamental design for an insulating siding corner unit, as shown.

ROBERT D. BORDEAUX.
